(57) **CLAIM**

The ornamental design for a floor fan, as shown and described.

DESCRIPTION

FIG. 1 is a front elevation view of a floor fan, showing our new design, with the rear grille removed for clarity of illustration;

FIG. 2 is a rear elevation view thereof, with front grille removed for clarity of illustration;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front perspective view thereof; and,

FIG. 8 is a rear perspective view thereof.

The broken lines in the drawings are for the purpose of illustrating portions of the floor fan that form no part of the claimed design.
